UNITED STATES PATENT OFFICE.

EDWIN W. PIERSON, OF NEWARK, NEW JERSEY, ASSIGNOR TO MERGENTHALER LINOTYPE COMPANY, A CORPORATION OF NEW YORK.

TYPOGRAPHICAL CASTING-MACHINE.

1,099,468.

Specification of Letters Patent.

Patented June 9, 1914.

Application filed June 13, 1913. Serial No. 773,474.

To all whom it may concern:

Be it known that I, EDWIN W. PIERSON, a citizen of the United States, residing at Newark, in the county of Essex and State 5 of New Jersey, have invented certain new and useful Improvements in Typographical Casting-Machines, of which the following is a specification, reference being had therein to the accompanying drawing.

10 My invention relates to typographical casting machines, such as linotype machines of the general organization represented in Letters Patent of the United States, No. 436532, to O. Mergenthaler, wherein circulating matrices are released from a magazine in the order in which their characters are to appear in print and then assembled in line, the composed line transferred to the face of a mold, the mold filled with molten 15 metal to form a slug or linotype against the matrices which produce the type characters thereon, and the matrices thereafter returned through a distributing mechanism to the magazine from which they started. 20 More particularly, it relates to the means for presenting the composed line to the mold, and is designed to vary automatically the extent of the presenting movement as different molds are called into service. 25 In machines of the class described, and particularly in linotype machines, it is customary to employ a plurality of molds of different dimensions, according to the character of the slug to be cast therein, as for 30 example, where the machine is equipped to produce either slugs having ordinary letters, or slugs having "head" letters, as may be desired. The characters on the head-letter matrices are of considerably greater 35 size than those on the ordinary matrices, and the respective mold slots vary correspondingly in width, and moreover, the positions of the characters on the respective 40 matrices are different. These differences in arrangement necessitate the arrest of the 45 first elevator or presenting means in different relative positions to the several molds, so as to effect the proper registration therewith of the composed lines of matrices. 50 This result has been previously effected in various ways not necessary here to detail at length.

It is the purpose of my present invention to accomplish the desired object automatically by the mechanical selection of the

mold, and more specifically, by means connected to the rotary mold carrier which act to interpose or withdraw the necessary stop, when the carrier is turned to bring a new mold into operative position.

60 In the accompanying drawings, I have shown my invention in preferred form and by way of example, and as applied to a linotype machine, but many changes and variations may be made therein, and in its mode of adaptation, which will be comprised within its spirit. Also, it may be applied to other forms of typographical casting machines, such as produce type or dies, instead of printing bars or slugs as 65 herein presented. Generally speaking, I desire it to be understood that I do not limit myself to any specific form or embodiment, except in so far as such limitations are 70 specified in the claims.

75 In the accompanying drawings: Figure 1 is a perspective view, partly in section, of the first elevator, the mold wheel, and the vise frame, with my invention applied thereto; Fig. 2 is a transverse section, on an enlarged scale, of two molds of different 80 dimensions, and showing also edge views of the respective matrices employed in connection therewith; Fig. 3 is a transverse 85 sectional view through the first elevator and vise frame; and Fig. 4 is a view similar to Fig. 1, but showing the parts in different position.

90 As is customary in the ordinary linotype machine, or as illustrated in the Letters Patent previously mentioned, the line composed of matrices X, or of matrices X', is lowered by the first elevator A into casting position between the jaws E and E' mounted upon the vise frame F, and so as 95 to register it with the mold C, or the mold D, carried by the rotary mold wheel or carrier B. The line is then justified, the mold wheel B advances to engage the mold therewith, and molten metal is injected into 100 the mold, all in the usual manner. The parts so far described are or may be of any well-known or appropriate character, such as are illustrated in the before-mentioned Letters Patent or employed in the ordinary 105 linotype machine, and their special construction and arrangement constitute no part of my present invention.

110 In the form illustrated, two molds C and D are shown as mounted in the wheel B.

The mold C is of the usual dimensions and is designed to coöperate with the ordinary matrices X. The mold D is formed with a larger mold slot and is intended to co-
5 operate with the head-letter matrices X'. It will be noted that the characters in the matrices X' are not only larger than those in the matrices X, but in addition are differently located thereon, and that the size
10 and location of the slots in the molds C and D correspondingly differ. It therefore becomes necessary to arrest the elevator A in different relative position to the mold wheel B, according to whether the mold C and
15 matrices X, or the mold D and matrices X', are in operation.

The extent of movement of the elevator A is normally controlled by the contact of the screw G with the vise frame F, and the necessary actuation of the rod J, frequently termed the "automatic", is effected by the screw H. The rod J corresponds to the rod indicated by the letter of reference a^{23} in the aforesaid Mergenthaler patent, and its
25 mode of operation is well understood by those skilled in the art.

In Fig. 4, the parts are shown with the mold C in casting position, at which time the elevator A descends until it is arrested by
30 the contact of the screw G with the vise frame F, when the rod J is moved by the screw H. This may be regarded as the regular or ordinary operation of the mechanism. When it is desired to employ a mold
35 and matrices of different character, such as the mold D in connection with the head-letter matrices X', the mold wheel B is swung about its axis until the parts assume the position indicated in Figs. 1 and 3. It is now
40 necessary that the elevator A be arrested at a higher point, and this is effected by the movement of the interponent K into position between the screw G and the vise frame F, and in order that the screw H may still actuate
45 the rod J, by the similar shifting of the interponent L over the top of the rod. The interponent K is shown as connected to the pivoted lever K' mounted upon the vise frame F, and the interponent L as connect-
50 ed to the spring arm L' connected to the lever K', so that the two interponents may be moved together into and out of operative position. Also pivotally mounted upon the vise frame F is the elbow lever M connect-
55 ed at one end to the lever K', and provided with the spring M' which normally holds it in engagement with the stop pin M², so that the parts occupy the positions shown in
60 Fig. 4. The other arm of the lever M projects outwardly from the vise frame F in position to be acted upon by one end of the lever N pivoted at N' to the main frame. The mold wheel B is provided with the abut-
65 ment O, mounted thereon in such relation to the mold D, that when the latter is brought

into the casting position, the abutment acts upon the other end of the lever N and swings it about its pivot. This movement of the lever N acting through the levers M and K', shifts the interponents K and L (Figs. 1
70 and 3) into operative position so as to arrest the elevator A at a higher point and still insure the actuation of the rod J, as previously described. When it is desired to resume the employment of the mold C, and
75 the mold wheel B is turned for that purpose, the abutment O is swung out of engagement with the lever N, and the spring M' restores the interponents K and L to in-
operative position as shown in Fig. 4. It
80 will thus be seen that the mechanical selection of the mold automatically adjusts the arresting means for the elevator, and that the operator is entirely relieved from the care and attention otherwise necessary, thereby minimizing the liability to maladjustment or disarrangement of the parts, and the disadvantages resulting therefrom. The outer end of the projecting arm of the elbow lever M is beveled as at M² to permit and
85 insure its free passage with relation to the end of the lever N, as for instance when the vise frame F is swung outwardly and then inwardly, as sometimes occurs in the em-
90 ployment of the machine.

As previously stated, I have shown my invention only in preferred form and by way of example, and as applied to a linotype machine, but obviously many alterations and modifications therein and in its mode of
95 adaptation will suggest themselves to those skilled in the art, without departure from its scope.

Having thus described my invention, its construction and mode of operation, what
105 I claim and desire to secure by Letters Patent of the United States, is as follows:

1. In a typographical casting machine, the combination of a plurality of molds capable of independent use, a matrix carrier
110 movable to different extents to correspond to one or another of the molds in use, and automatic means to determine the extent of movement of the carrier.

2. In a typographical casting machine, the combination of a plurality of molds capable of independent use, a matrix carrier movable to different extents to correspond to one or another of the molds in use, and means whereby the mechanical selection of a mold
120 automatically varies the extent of movement of the carrier to correspond therewith.

3. In a typographical casting machine, the combination of a plurality of molds, a matrix-presenting device, and means for bringing any selected mold into action and simultaneously varying the relation of the presenting device thereto.

4. In a typographical casting machine, the combination of a plurality of interchange-

- able molds, a matrix carrier movable to different extents, and means whereby an interchange of molds effects a change in the extent of movement of the carrier.
5. In a typographical casting machine, the combination of a mold carrier movable to bring a selected mold into action, a matrix-presenting device movable to different extents, and adjustable means controlled in 10 their adjustment by the movement of the mold carrier to vary the extent of movement of said presenting device.
6. In a typographical casting machine, the combination of a plurality of movable 15 molds, a movable matrix carrier, and adjustable means for arresting the matrix carrier in different positions, the said means being controlled in their adjustment by the movement of the molds.
- 20 7. In a typographical casting machine, the combination of a plurality of molds, any selected one of which may be brought into action at will, a movable matrix carrier, a stop device to arrest the movement of the 25 carrier and movable to active and inactive position, and means associated with the molds to locate said device in its active or inactive position, according to which of the molds is brought into action.
- 30 8. In a typographical casting machine, the combination of a mold carrier movable to bring a selected mold into action, an elevator to carry the matrix line to and from the mold, a stop device to arrest the movement of the elevator and movable to active and inactive position, and means controlled by the movement of the mold carrier to move the stop device to active or inactive position, as required.
- 40 9. In a typographical casting machine comprising matrices, the combination of a plurality of molds capable of independent use, means for determining the operative relation between the matrices and the mold
- in use, and devices associated with the molds 45 for automatically controlling the actuation of said means to correspond with the one in use.
10. In a typographical machine, the combination of a plurality of molds capable of 50 independent use, a matrix line carrier movable to different extents to correspond with the mold in use, a clutch controlling rod operated by the movement of the carrier, and means whereby a change of mold will 55 vary the extent of movement of the carrier and automatically provide for the operation of the clutch controlling rod.
11. In a typographical machine, the combination of a plurality of molds capable of 60 independent use, a matrix line carrier movable to different extents to correspond with the mold in use, a clutch controlling rod operated by the movement of the carrier, a device adapted to be interposed between 65 the rod and the carrier according to the extent of movement of the latter, and means whereby a change of mold will move the said device into or out of its operative position. 70
12. In a typographical composing machine, the combination of a plurality of molds capable of independent use, a matrix line carrier movable to different extents to correspond to the mold in use, a clutch controlling rod adapted to be operated by the carrier, and means whereby the mechanical selection of a mold automatically determines the extent of movement of the carrier and also provides for the operation of the clutch 75 controlling rod to correspond therewith. 80

In testimony whereof I have affixed my signature in presence of two witnesses.

EDWIN W. PIERSON.
